(57) **CLAIM**

The ornamental design for a paint dispenser with dual brush wipers, as shown and described.

DESCRIPTION

FIG. 1 is a top right perspective view of the paint dispenser with dual paint wipers showing the present invention, the broken line disclosure of a person's hands holding the dispenser and a brush so as to wipe it across the top of or the wiping structure as being shown for illustrative purposes only and forming no part of the claimed design;

FIG. 2 is a top front perspective view of the paint dispenser according to FIG. 1;

FIG. 3 is a top plan view of the paint dispenser;

FIG. 4 is a front elevational view of the paint dispenser;

FIG. 5 is a rear elevational view of the paint dispenser;

FIG. 6 is a bottom plan view of the paint dispenser

FIG. 7 is a right side perspective view of the paint dispenser; and,

FIG. 8 is a cross-sectional view thereof taken along line 8—8 of FIG. 3.
